UNITED STATES PATENT OFFICE

MAX SCHNEIDER AND CLARA G. SCHNEIDER, OF DENVER, COLORADO.

SPRAYING DEVICE.

1,092,865.

Specification of Letters Patent. Patented Apr. 14, 1914.

Application filed April 26, 1913. Serial No. 763,743.

To all whom it may concern:

Be it known that we, MAX SCHNEIDER and CLARA G. SCHNEIDER, the said MAX SCHNEIDER being a subject of the King of Germany and the said CLARA G. SCHNEIDER being a citizen of the United States, residing in the city and county of Denver and State of Colorado, have invented certain new and useful Improvements in Spraying Devices; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to improvements in spraying devices in which a receptacle containing a poisonous liquid adapted to kill germs or vermin injurious to trees or shrubbery, may be automatically mingled with the water in proper proportion during the spraying operation, our improvement being capable of attachment to an ordinary garden hose.

The receptacle containing the poisonous liquid or chemical is mounted on the nozzle in such a manner that as the water from the hose passes through the nozzle, an auxiliary passage which is in communication with the said receptacle is surrounded by the issuing stream of water which serves to convert the poisonous liquid into a spray which is thoroughly mingled with the water forming a homogeneous mixture which may be delivered to the trees, shrubbery or other vegetation in such quantities as may be desired, provision being made for regulating the escape of the poisonous liquid whereby the quantity of the latter used is properly proportioned to the water passing through the nozzle. Provision is also made for pivotally connecting the said receptacle with the nozzle in such a manner that the receptacle is automatically maintained in an upright or vertical position regardless of the position of the hose nozzle when the device is in operation, the proper counterbalancing of the receptacle being accomplished by means of a weight of sufficient mass to support the receptacle in a sufficiently stable condition.

Having briefly outlined our improved construction, we will proceed to describe the

same in detail, reference being made to the accompanying drawing in which:

Figure 1 is an elevation of a hose nozzle equipped with our improvement, the hose to which the nozzle is attached being broken away quite close to the place where the nozzle is connected. Fig. 2 is a vertical section taken through the liquid receptacle on line 2—2; Fig. 1, looking toward the left or in the direction of the arrow. Fig. 3 is a longitudinal sectional view of the nozzle taken on the line 3—3, Fig. 2.

The same reference characters indicate the same parts in all the views.

Let the numeral 5 designate the hose and 6 the nozzle attached thereto, the said nozzle being provided with a main passage 7 through which the water passes, and a centrally located interior auxiliary member 8 having a relatively small passage 9, the said member 8 projecting through an opening 10 formed in a cap 12 applied to the threaded body portion 13 of the nozzle. The centrally located member 8 tapers toward its outer extremity 14 which extends a short distance beyond the perforation 10 in the cap of the nozzle. As this cap is screwed inwardly, or toward the hose, the perforation 10 through which the water issues is gradually contracted, thus diminishing the flow of water. It is evident that the movement of the cap in the opposite direction will have the opposite effect, that is, to increase the flow of water through the nozzle. The member 8 of the nozzle has an abrupt turn at its inner extremity as shown at 15 and its passage registers with an opening 16 formed in the side of the body of the nozzle, the latter being exteriorly equipped with a threaded nipple 17 upon which is screwed a cylindrical boss 18 having a cavity 19 into which is fitted a nipple 20 with which the cone-shaped lower portion 21 of the receptacle 22 is provided.

The passage of the liquid through the nipple 20 from the receptacle 22 is regulated by a needle valve 23 connected with the lower extremity of the stem 24 upon which is mounted an adjustable stop 25, the said stop being connected with the stem by a set screw 26. Surrounding the stem above the stop, is a spiral spring 27 whose lower extremity engages said stop and whose upper extremity bears against a cross piece 28

through which the upper portion of the stem passes and in which the said stem slides freely. The upper extremity of the stem extends above the top of the receptacle and 5 is provided with a knob 29 to which is rigidly attached a sort of pointer 30 adapted to engage an inclined and notched edge 31 formed on the upper portion of the receptacle and graduated as a guide to the operator 10 in regulating the escape of liquid from the receptacle in order to properly proportion the same to the passage of water through the nozzle. As the knob and stem are turned in one direction, the pointer 15 moves upwardly on the notched inclined edge and temporarily maintains the stem in the proper position of adjustment. As the pointer moves upwardly on the notched edge 21, the stem is lifted against the tension of 20 the spring 27 and the needle valve raised to increase the opening through the nipple 20 available for the passage of the liquid from the receptacle into the auxiliary nozzle member 8. If the pointer 30 is adjusted to 25 occupy a position about midway of the inclined edge 31 of the receptacle, a sort of spring pawl or dog 32 is made to occupy a circumferential groove 33 intermediate two other grooves designated 34 and 35 respectively. The notched edge 31 of the receptacle and the circumferential grooves upon the body of the nozzle are so arranged that the operator may understand from the relative 30 positions of the pointer 30 and the pawl 32, the relative proportions of the two liquids 35 employed for spraying purposes.

Threaded into the boss 18 at the lower side thereof as shown at 36 is a depending stem 37 to whose lower extremity is attached 40 a ball 38 preferably solid and composed of a lead. This ball should be of sufficient mass to counterbalance the receptacle 22 when the latter contains a suitable quantity of liquid 39. The nipple 20 is tightly fitted 45 into the cavity in the boss 18, being slightly tapered to fit the upper part of the said cavity, the engaging parts being fashioned to form a ground joint. The connection between the threaded nipple 17 and the boss 50 18 while threaded, is nevertheless sufficiently loose to permit the receptacle 22 under the influence of the weight 38, to maintain at all times a vertical position regardless of the angle which the nozzle 6 occupies with 55 reference to the stem 37. In order to make this relatively loose joint liquid tight, we employ a gasket 40 interposed between the boss and the nozzle and surrounding the threaded nipple.

60 In order to prevent leakage between the cap 12 and the body of the nozzle, the latter is provided with an exteriorly projecting collar 41 which is engaged by a gasket 42 preferably composed of rubber or some 65 similar or suitable material adapted to per-

form the required function. Against this gasket 42 is screwed a washer 43 causing the gasket to protrude sufficiently circumferentially whereby when the rear enlarged extremity 44 of the cap is applied to the nozzle and surrounds the said gasket, a perfectly tight joint will be formed. 70

From the foregoing description the use and operation of our improved spraying device will be readily understood. Assuming that the parts are assembled in substantially the manner illustrated in the drawing, the nozzle cap and the stem 24 should be adjusted in relation to each other so that the proper proportion of liquid from the receptacle 22 will be mingled with the water issuing from the opening 10 of the nozzle in order to give the resulting liquid product the necessary strength for germ and insect destroying purposes, and for this purpose 80 the receptacle is provided with indicia, as numerals adjacent the notched inclined edge 31 of the top of the receptacle, while the body of the nozzle is provided with the circumferential grooves 33, 34 and 35, the grooves being so arranged with reference to the numerals on the receptacle that the operator will understand the proper relative positions of the pointer 30 and pawl 32, required to give the desired result. It 85 will be understood that the cap 12 is so regulated as to allow water to escape through the opening 10 and around the auxiliary nozzle 8, while the position of the needle valve must be such as to allow liquid to pass 90 downwardly around the same and through the nipple 20 when our improved spraying device is in operation, assuming that it is desired to mix the liquid in the receptacle 22 with the water from the hose 5. Of course, 95 the needle valve may be closed if for any reason it should not be necessary to employ the liquid in the receptacle 22. In this event, the nozzle will perform the ordinary function which it will, of course, do independently of the liquid in the receptacle 22 100 when there is no occasion for using this liquid. 110

From the previous description, it will be understood that while the liquid from the 115 receptacle 22 passes downwardly by gravity and by virtue of the pressure within the receptacle, it would pass through the auxiliary nozzle 8 and escape from the outer extremity thereof, the issue of the 120 liquid from the auxiliary nozzle is facilitated by the suction, resulting from the issuing stream of water from the main nozzle (which stream surrounds the escape extremity of the auxiliary nozzle) on the 125 atomizer principle. Furthermore, it will be understood that by virtue of the relative arrangement of the two nozzle members, the liquid 39 within the receptacle 22 will be thoroughly mingled with the water, the 130

various parts of the structure being properly adjusted to give the proper proportions of water and germ destroying liquid.

Having thus described our invention,
5 what we claim is:

1. In combination, two nozzle members, arranged in suitable proximity, and having their discharge extremities arranged to produce an atomizing effect, a cap mounted 10 upon one nozzle member for regulating said effect, a main water supply conduit in communication with one nozzle member, a receptacle for poisonous liquid in communication with the other nozzle member, the said 15 receptacle being mounted on the nozzle structure by a joint sufficiently loose to permit it to maintain an upright position above the nozzle members, regardless of the relative position of the nozzle structure, and a 20 counterbalance weight connected with the said receptacle and extending below the joint.
2. In a device of the class described, and in combination, a water supply, a main nozzle in connection with said supply, an auxil- 25

iary nozzle within the main nozzle and extending beyond the outward extremity of the latter, said extension being provided with a flange to produce a spraying effect, a cap mounted on the main nozzle to regulate said spray, a nipple carried by the main nozzle and communicating with the auxiliary nozzle, a liquid receptacle communicating with said nipple and movably supported thereby in a position above said nozzle, 30 and counterbalanced to maintain an upright position, a valve for controlling the discharge of liquid from said receptacle to said nipple, and means for adjusting the valve to properly regulate the proportion of liquid 35 passing from the receptacle to the auxiliary nozzle as compared with the liquid passing through the main nozzle.

In testimony whereof we affix our signatures in presence of two witnesses.

MAX SCHNEIDER.

CLARA G. SCHNEIDER.
